UNITED STATES PATENT OFFICE.

RICHARD L. HULL, OF MERIDEN, CONNECTICUT.

LANTERN.

SPECIFICATION forming part of Letters Patent No. 289,348, dated November 27, 1883.

Application filed March 15, 1883. (No model.)

To all whom it may concern:

Be it known that I, RICHARD L. HULL, of Meriden, in the county of New Haven and State of Connecticut, have invented a new and 5 useful Improvement in Lanterns; and I hereby declare the following to be a full, clear, and exact description of the same, reference being had to the accompanying drawings, forming a part of this specification.

10 This invention has reference to an improvement in the construction of portable lanterns; and it consists in the peculiar and novel construction, with the lantern, of the oil-chamber, and the manner of securing the same, as will 15 be more fully set forth hereinafter.

In portable lanterns the oil-receptacle or lamp is usually made separate from the frame of the lantern, so that it can be readily removed, refilled, trimmed, lighted, and re- 20 placed. As such lanterns are specially used in stables, warehouses, and other places where the nature of the contents make the risk of fire specially hazardous, it is important that the 25 connection between the lamp and lantern should be secure, firm, and not liable to become loose. A bayonet connection has heretofore been used to connect the lamp, but the 30 projecting pins have to be secured by solder at the ends, making this a weak and uncertain connection.

In my improved lantern I form a coarse screw-thread on the body of the lamp and on the flanged bottom of the lantern, and place an 35 annular ring on the lamp provided with a locking-notch, and construct a spring-pressed latch to enter the locking-notch and hold the lamp, thus making a firm connection not liable to 40 separate.

Figure 1 is a view of my improved lantern, 45 the connection of the oil-reservoir or lamp with the lantern being shown in section. Fig. 2 is a bottom view of the lantern, showing the 50 spring-latch for holding the lamp against rotation.

45 In the drawings, A A is the metal framework of the lantern. B is the glass inclosing the lamp. C is the bottom; D, a circular flange formed into a nut or female screw-thread, into which the lamp E, provided with the screw- 55 thread e, is screwed, as is shown in Fig. 1. The screw-thread e may be formed on the

chamber of the lamp E, or a ring formed into such a screw-thread may be soldered or otherwise secured to the lamp. The screw is preferably made so that one turn of the lamp will 55 firmly secure the same. To the lamp E, the ring F is secured to form a guide for entering the screw-thread and a lock for securing the same. The ring F is provided with the notch f and the shoulder g, and to the bottom is secured the spring-latch h. When the lamp is to be entered the hook of the spring h is placed in the corner against the shoulder g, thus forming a guide for entering the screw on the lamp into the nut formed on the bottom. By turning 60 the lamp the screw at once engages, and when it is fully entered the spring-latch enters the notch f, and firmly holds the same in place. Instead of the spring-latch h any other form of 65 spring-latch may be used. The screw-thread 70 e is shown continuous; but it may be constructed in sections—that is to say, the circumference may be divided into four or six parts, and two or three, as the case may be, of the parts be formed into screw-threads, 75 while the other parts are recessed so that the alternate screw-threads on the lamp will enter the recessed spaces in the flange D, and the one-sixth or one-fourth turning of the lamp will 80 secure the same with any desired number of screw-threads, so that the lamp can be more firmly secured and yet more quickly removed than with a continuous screw-thread. When the sectional screw is used, the ring F is provided with two or three notches, f, so as to lock 85 the lamp against rotation.

Having thus described my invention, I claim as new and desire to secure by Letters Patent—

The combination, with the frame A, the bottom C, and the threaded flange D, of the lamp 90 E, provided with the screw-threads, constructed to enter the threaded flange, the ring F, provided with the notch f, and a latch constructed to enter the notch on the ring F and secure the lamp against rotation, as described. 95

In witness whereof I have hereunto set my hand.

RICHARD L. HULL.
